ATTORNEY

UNITED STATES PATENT OFFICE

133,411

DESIGN FOR A PREFABRICATED HOUSE

Richard Buckminster Fuller, New York, N. Y.,
assignor to The Dymaxion Company, Inc., Wil-
mington, Del., a corporation of Delaware

Application May 31, 1941, Serial No. 101,241

Term of patent 14 years

To all whom it may concern:

Be it known that I, Richard Buckminster Fuller, a citizen of the United States, residing at New York, in the county and State of New York, have invented a new, original, and ornamental Design for a Prefabricated House, of which the following is a specification, reference being had to the accompanying drawing, forming a part thereof.

In the drawing,

Figure 1 is a front elevational view of a pre-fabricated house embodying my new design.

Figure 2 is a top plan view of said prefabricated house.

I claim:

The ornamental design for a prefabricated house, as shown.

RICHARD BUCKMINSTER FULLER.
